UNITED STATES PATENT OFFICE.

ARTHUR F. BRASSINGTON, OF PORT RICHMOND, NEW YORK.

CHIMNEY CAP OR VENTILATOR.

1,380,882.

Specification of Letters Patent. Patented June 7, 1921.

Application filed May 24, 1920. Serial No. 383,696.

To all whom it may concern:

Be it known that I, ARTHUR F. BRASSINGTON, a citizen of the United States, residing at Port Richmond, in the county of Richmond and State of New York, have invented 5 certain new and useful Improvements in Chimney Caps or Ventilators; and I do hereby declare the following to be a full, clear, and exact description of the invention, 10 such as will enable others skilled in the art to which it appertains to make and use the same.

My invention consists in the novel features hereinafter described, reference being 15 had to the accompanying drawings which illustrate several forms or embodiments of my invention, selected by me for purposes of illustration, and the said invention is fully disclosed in the following description and 20 claims.

The object of my invention is to provide a chimney cap or ventilator to be applied to the upper end of a flue for conducting foul air or the products of combustion from a 25 stove or furnace out of a building, and is particularly applicable to the locations in which the discharge outlet of the flue is adjacent to a blank wall of another building of greater height as frequently happens in 30 thickly settled communities where houses of different heights adjoin each other or are closely placed, although I do not limit myself to the use of my improved device in such circumstances. Where the discharge orifice of 35 a chimney or flue communicates with the atmosphere at a point adjacent to the wall of an adjoining building, which extends considerably above the level of the discharge opening and also to a considerable extent on one 40 or both sides of the same, it is particularly difficult to obtain the necessary upward draft through the flue, as there is a tendency for the air, especially if the wind is blowing in a direction toward the higher wall, to 45 strike the wall and circulate downwardly toward the lower structure and produce a down draft in the flues thereof. I have discovered, by a series of experiments, that if 50 an eduction pipe communicating with the flue, is provided with a deflector of the same form, and of the same or preferably slightly greater area or size than the discharge orifice of the eduction pipe, placed across the orifice, and spaced a short distance there-

from, so as to provide a narrow outlet 55 around the edges of the deflector, which outlet is surrounded by an inclosing band or sleeve equally spaced from the edges of the deflector and extending on both sides of the eduction orifice so formed, the passage of air 60 between the band or sleeve and the edges of the deflector or eduction pipe in any direction will have the effect of creating a partial vacuum and withdrawing the contents of the eduction pipe and flue. This action 65 will take place no matter how gently or strongly the motion of the outside air (breeze or wind) may be. I also find that this effect is increased beneficially by making the face of the deflector adjacent to the discharge orifice of the eduction pipe convex 70 (either spherically, pyramidal, or conically) so that its apex or highest point extends into the discharge orifice of the pipe to a greater or less extent. The exterior face 75 of the deflector may be correspondingly concave, or it may be a plane surface if preferred, perpendicularly disposed to the axis of the discharge passage, although I prefer that the outer face of the deflector should be 80 concave and should correspond with the inner face, being conveniently formed in this manner from sheet metal. I also prefer, in carrying my invention into effect, to increase the size and capacity of the eduction 85 pipe adjacent to the discharge orifice by flaring the walls of the pipe outwardly so that the narrow slit or discharge orifice formed between the outer edge of the flared opening of the pipe and deflector, while it is of narrow width, shall have sufficient extent in the opposite direction around the edges of the orifice and deflector to insure a discharge capacity substantially equal to or greater 90 than the capacity of the flue with which the 95 device is connected.

In carrying my invention into effect, I may provide a flue with one or more of these devices located on opposite sides of a vertical axis, or I may employ a plurality of these 100 devices, of different sizes, located on the same side of a vertical axis, in which case the eduction pipe may be provided with one or more axially aligned extensions of gradually decreasing diameter and capacity communicating with the eduction pipe and flue.

Referring to the accompanying drawings, Figure 1 represents a side elevation of a

chimney cap or ventilator embodying the preferred form of my invention.

Fig. 2 is an end elevation of the same.

Fig. 3 is a longitudinal vertical sectional view of the device.

Fig. 4 is a vertical transverse section on line 4—4 of Fig. 1.

Fig. 5 is a partial longitudinal sectional view similar to Fig. 3, showing a modification of my invention in which a plurality of my improved devices of different diameters are employed in connection with a single eduction pipe.

Fig. 6 is a side elevation of another modified form of my invention in which a single vertical elongated eduction apparatus is provided.

Fig. 7 is a vertical sectional view of the device shown in Fig. 6.

Fig. 8 is an end elevation of the same.

Fig. 9 is a horizontal section on the line 9—9 of Fig. 7.

Fig. 10 is a sectional view of another modification in which four discharge apertures are provided.

Referring to the preferred form of my invention illustrated in Figs. 1, 2, 3, and 4, 1 represents a delivery pipe which may be connected to a flue, chimney or a space of other character, the gaseous content of which is to be withdrawn. 2 represents a horizontally disposed eduction pipe, which preferably has its central portion in communication with the vertical delivery pipe 1, and is open at its opposite ends to form two horizontal eduction passages. The eduction pipe 2 may be of any desired form, but I prefer to make it rectangular in cross section and set diagonally, as shown in Fig. 2, that is to say, so that one of the diagonals connecting opposite corners shall be vertical and the other horizontal. I prefer this construction as it provides for the ready shedding of rain, snow, etc., to which the device is necessarily exposed. Each end of the pipe 2 is provided with a transversely disposed deflector 4, which is of the same form marginally as the end of the flared portion 3, that is to say, rectangular or square, but is of

greater area, so that the edges of the deflector, indicated at 4^a, extend laterally beyond the edges of the flared portion 3, indicated at 3^a, all the way around, as clearly indicated in Figs. 3 and 4. This construction provides a discharge orifice, indicated at 5, which extends entirely around the outer edge of the flared portions 3, and the deflector 4, for the escape of smoke, products of combustion, heated air, or other contents of the flue and delivery pipe 1. The deflectors 4—4, as shown, are preferably each provided with a convex inner face extending into the orifice formed by the outer edges of the flared portions 3—3, as clearly shown in Fig.

65 3, and in this instance the deflectors are

formed of sheet metal so that their exterior faces are correspondingly concave. These deflectors are therefore of pyramidal shape, but I wish it to be understood that they may be of conical shape, or in the form of a segment of a sphere, if preferred. It is not absolutely necessary that the exterior faces of the deflectors shall be concave, although I prefer to make them in this way for the sake of economy and to secure the greatest efficiency. In some instances they may be made with plane exterior faces, as indicated at 6, at the left in Fig. 3, in which I have shown one deflector made with the plane exterior face and the other with a concave exterior face in order to illustrate both constructions. It will be obvious that in either case all parts of the deflector are on one side of a plane indicated by the dotted line X—X in Fig. 3, passing through the edges of the outer face of the deflector. The deflectors 4—4 may be supported in any desired or usual manner. In the present instance I have shown them supported by means of brackets, indicated at 7—7 formed of thin sheet metal set edgewise, so that they will not obstruct the discharge orifice 5 or slit. Surrounding this discharge orifice or slit at each end of the device is a sleeve or band indicated at 8 which is preferably formed of sheet metal and bent in the same form as the outer edges of the deflector and spaced uniformly therefrom, as indicated in Figs. 2, 3, and 4, the said bands being supported in any desired manner, as for example, by means of sheet metal brackets 9, also placed edgewise, so as not to interfere with the free passage of air between the band and the edges of the deflector, and the flared portion 3. The band is so disposed that it projects on both sides of a plane passing through the edges of the deflector, as clearly indicated in Fig. 3.

In practice this device is installed at the top of a chimney or flue with which the vertical delivery pipe 1 is connected, and is stationarily supported. In case there is an adjoining blank wall, one end of the apparatus is preferably directed toward the blank wall, the position of which is indicated in Fig. 3 by the dotted line W—W. If the direction of the wind is in the direction of the arrow at 10 in Fig. 3, the air will impinge against the outer face of the deflector at the left hand end of the device, as shown in that figure, and be forced to pass under slight compression between the edges of the deflector and the band 8 and across the discharge orifice, thereby affecting a rarefaction of the air, or in other words, producing a partial vacuum and causing the smoke to be drawn out of the pipe 2, as indicated by the arrows 11—11. At the other end of the apparatus, the air passing in the direction of the arrows 12—12 will be forced by the

flared portions 3 toward the inner face of the band 8, and between it and the edges of the deflector 4, and this will produce a partial vacuum at the discharge orifice and cause the smoke to be drawn out, as indicated by the arrows 13—13, notwithstanding the presence of the wall W—W. If the direction of the wind is such that it tends to bank against the wall W—W above the apparatus and be deflected downwardly, it will pass through the apparatus in a direction opposite to that indicated by the arrows 10 and 12, with a correspondingly opposite effect, which will nevertheless withdraw the smoke and other contents of the delivery pipe 1 and eduction pipe 2, through both of the discharge orifices 5—5, and as a matter of fact, the device is so constructed that no matter from which direction the air is moving, it will pass through the spaces between the bands 8 and the outer edges of the deflectors in one direction or the other and in either direction will effect a rarefaction at the discharge orifices and withdraw smoke or other gases within the pipes 1 and 2. It is found in practice that it is impossible for any of the outside air to be blown down the flue no matter how strong the wind is blowing or from which direction, or whether upwardly or downwardly, and that in all directions, the passage of air currents through and around the apparatus, produces a distinct suction and withdraws the contents of the pipes 1 and 2 and of the flue connected therewith. It will be understood that while I prefer to employ the duplex form of the device shown in Figs. 1, 2, 3, and 4, as each end of the apparatus is a duplicate of the other, and each is extremely efficacious, I may dispense with one of the discharge orifices and close the horizontal pipe 2 at one end, if desired, and as indicated in Figs. 6 to 9 hereinafter more particularly described.

In Fig. 5 I have shown a modification of my invention in which I employ a plurality of eduction pipes of different diameters, each provided with a deflector and surrounding band which construction may be arranged at one or both ends of a horizontal eduction pipe, indicated at 102, and connected with a delivery pipe 101. In this instance the pipe 102 is provided with a flared portion 103 at the open end of which is located the deflector 104 having its inner face convex and its outer face plane, as indicated at 106, and forming the discharge orifice 105. In this case the deflector, which is supported by brackets 107, is made in annular form and surrounds a pipe section 102^a which forms a continuation of the eduction pipe 102, and the outer end of pipe section 102^a is provided with a similar deflector 104^a provided with a central opening surrounding a pipe 102^b forming a further extension of the eduction pipe 102, and hav-

ing at its outer end a deflector 104^b. The deflector 104 is surrounded by the band 108, supported on brackets 109, the deflector 104^a being surrounded by a band 108^a, and the deflector 104^b being surrounded by a band 108^b, of still smaller diameter, it being understood that each of the deflectors projects slightly beyond the edges of the eduction orifice of the pipe into which it extends, in the manner previously described. The operation of the apparatus shown in Fig. 5 is substantially identical with the operation previously described, except that the partial vacuum referred to is produced at each of the eduction apertures or slits and the withdrawal of smoke may be effected more rapidly than were only one of the eduction orifices provided. This construction will therefore be of particular advantage in connection with chimneys where wood or soft coal is burned, and large volumes of heavy smoke are evolved, while I prefer a single form of apparatus hereinafter described or the duplex form shown in Figs. 1 to 4 inclusive for ordinary purposes.

In Figs. 6 to 9, I have shown a construction similar to half of the apparatus shown in Figs. 1 to 4 inclusive, except that the device is elongated vertically, and this form may be especially convenient for use in connection with pipe circular in cross section. In these figures 201 represents the delivery pipe, the upper end of which is cut away at one side and closed at the upper end to provide an eduction chamber 202 having a rectangular opening at one side, into which extends the convex deflector 204 supported by the brackets 207 and providing a rectangular discharge passage 205 between the convex face of the deflector and the edges 203 of the eduction chamber. 208 represents a band or sleeve, here shown as of rectangular form supported by brackets 209 and surrounding the edges of the deflector 204 and the edges 203 of the eduction chamber. As will readily be seen, the passage of air through the band 208 between it and the edges of the deflector in either direction will produce a partial vacuum at the discharge orifice surrounding the deflector and withdraw the smoke or other gaseous material within the delivery pipe 201 and the eduction chamber 202 and the flue connected therewith.

While my improved apparatus is especially adapted for use as a chimney cap on buildings, it may also be used for withdrawing smoke or for ventilating purposes on ships, railway cars, or other moving vehicles for the removal of dust-laden air or other contaminated air or gases from the interior of buildings or other structures, or wherever its use may be found to be advantageous.

As hereinbefore stated, I prefer to form the deflectors with concave exterior faces.

One beneficial effect of this concavity is to cause the air, if it is blowing in a direction toward the concave face, to sweep around the edges of the deflector in a wider curve 5 or curve of greater diameter than where the outer face of the deflector is a plane surface, thus increasing the suction or rarefaction produced at the discharge aperture, and increasing the efficiency of the apparatus in 10 withdrawing the contents of the eduction pipe.

In Fig. 10 I have illustrated another modification of my improved chimney cap or ventilator in which the vertical delivery pipe 301 is provided with four horizontal eduction pipes, indicated at 302, arranged in pairs opposite each other, and disposed radially with respect to the longitudinal axis of the delivery pipe 301. In this instance each 20 of the eduction pipes 302 is provided with a deflector 304 extending across the open end of the eduction pipe and being of slightly greater area than the orifice of the eduction pipe, the deflector being provided with a 25 convex inner face, as previously described, and the outer face being either concave or plane, and a discharge orifice being formed between the deflector and the edges of the eduction opening, as indicated at 305. Surrounding each of the eduction pipes and deflectors is a band 308 spaced uniformly from the edges of the deflector and extending on both sides of the discharge slit or aperture 305. This form of the apparatus, while 30 more expensive than the single or double form hereinbefore described, is very efficient. Obviously wind from almost any direction will strike directly against the outer face of one of the deflectors, passing over the 40 same within the band, and creating rarefaction with the attendant withdrawal of smoke or gases from the interior of the eduction pipe and delivery pipe, and will effect a similar operation in passing within the band 45 and around the edges of the deflector at the end of the radially opposite eduction pipe, while cross currents or eddies passing through the bands of the laterally disposed eduction devices on each side of the path of 50 the breeze will also contribute to the same result.

In some instances where the delivery pipe is provided with a plurality of eduction orifices, I prefer to provide a vertically disposed partition or partitions, substantially in alinement with the axis of the delivery pipe, for the purpose of stabilizing the smoke and gases in the upper portion of the eduction pipe and providing for the distribution or separation of the ascending current of smoke or gases into branch currents leading to the several discharge orifices, without, however, throttling the smoke or gases. Thus, in Fig. 3, for example, I have shown 60 a vertically disposed partition 15 arranged

transversely across the upper portion of the eduction pipe 2, midway between the two discharge orifices 5 and in alinement with the longitudinal axis of the delivery pipe 1. This partition may, however, be dispensed with in some instances if desired. 70

In the manufacture of my improved apparatus I prefer to employ tubing for the delivery pipe and eduction pipe or pipes, which is rectangular in cross section, and 75 preferably square. As a moving current of smoke, air, or gas, has a tendency to form itself into a mass circular in cross section, less frictional resistance is offered to the passage of smoke or air or gas through a 80 tubular passage which is square in cross section than one which is circular in cross section. The delivery pipe and eduction pipes are also made of sufficiently large size as to insure at all times the utmost freedom for 85 the passage of the gaseous products which are desired to be withdrawn. I also prefer to form the deflectors with a square base and a pyramidal inner face, as shown and hereinbefore described, as the length of the surrounding discharge orifice or slit, which will be substantially equal to the sum of the four sides of the square, will necessarily be greater than the circumference of a circle having the same diameter. Therefore, by 90 this means, I am enabled to obtain a discharge slit or opening of greater area without increasing the width of the slit. 95

As before stated the capacity of the discharge slit between the deflector and the 100 edges of the outlet aperture of the eduction pipe is as great as or greater than the capacity of the eduction pipe, so that there is no throttling or retarding of the smoke or other gases discharged. The space between 105 the exterior sleeve, and the edges of the discharge slit is, as shown, of greater capacity than the discharge slit, and the passage of air (wind) therethrough in any direction not only does not retard or baffle the discharge from the eduction pipe but accelerates it by causing a partial vacuum adjacent to the edges of the deflector, and there is therefore no back draft under any circumstances. 110

What I claim and desire to secure by Letters Patent is:— 115

1. In a chimney cap or ventilator, the combination with an eduction pipe, provided with an outlet aperture, of a deflector of an area at least as great as said aperture supported rigidly and permanently transversely across said aperture, and spaced from the edges thereof so as to provide a delivery slit having an area substantially equal to that of the eduction pipe, and a sleeve surrounding the edges of said aperture and deflector, and separated therefrom uniformly around the same to form a space having a greater area than that of the delivery slit, said sleeve extending partly over said educt- 120 125 130

tion pipe and having a portion extending beyond the end of said pipe provided with an aperture of greater area than said education pipe, whereby back drafts and the retarding of the gases passing through said education pipe are prevented and whereby the delivery of gases from said education pipe is facilitated by the passage of air through the space within said sleeve in either direction.

2. In a chimney cap or ventilator, the combination with a vertical delivery pipe, of a horizontally disposed education pipe communicating therewith and provided with a coaxial discharge aperture, a vertical deflector disposed transversely across said aperture, said deflector being of a size at least as great as that of said aperture, said deflector being rigidly and permanently supported at such a distance from the edges of said aperture as to provide a discharge slit having a cross sectional area at least as great as that of the delivery pipe and a sleeve coaxial with the education pipe extending around the edges of said slit, and separated therefrom so as to provide a space of at least as great cross sectional area as the delivery slit, said sleeve extending beyond the end of the education pipe and having an aperture at its outer end of greater area than the delivery pipe.

3. In a chimney cap or ventilator, the combination with an education pipe provided at its discharge end with outwardly flared portions forming a discharge aperture of greater area than the pipe, a deflector having an area at least as great as said aperture permanently and rigidly supported across said aperture, and spaced therefrom to form a narrow discharge slit of a cross sectional area at least as great as that of the education pipe, and a coaxial sleeve supported around the edges of said flared portions of the education pipe and of said deflector and separated therefrom so as to form a passage, of an area greater than that of the discharge, the said sleeve extending beyond the end of said flared portions and having an aperture at its outer end of greater area than that of the discharge slit.

4. In a chimney cap or ventilator, the combination with a vertically disposed delivery pipe, provided at its upper end with horizontally disposed education passages extending in opposite directions and terminating in education apertures, a deflector having at least as great an area as said apertures permanently and rigidly supported transversely across each of said apertures, and spaced therefrom to form discharge slits or openings extending around the edges of said apertures and deflectors, the cross sectional area of said slits being at least as great as that of the delivery pipe, and a sleeve surrounding each of said deflectors and sepa-

rated from the edges thereof to form a passage having an area greater than that of said slits.

5. In a chimney cap or ventilator, the combination with a vertically disposed delivery pipe closed at its upper end and provided with a plurality of horizontally disposed education passages communicating therewith and terminating in education apertures, and extending in different directions radially with respect to the longitudinal axis of the delivery pipe, certain of said passages being disposed angularly with respect to others, a deflector permanently and rigidly supported across each of said education apertures, said deflectors having at least as great an area as said apertures, and being spaced uniformly from the edges of said apertures, and a sleeve surrounding each of said horizontally disposed education passages coaxial therewith and spaced uniformly from the edges of said deflector and education apertures, each of said sleeves having an aperture at its outer end of greater area than the adjacent education passage.

6. In a chimney cap or ventilator, the combination with a vertically disposed delivery pipe having its upper end closed and provided with a plurality of horizontally disposed education passages terminating in education apertures, said passages being disposed radially with respect to the longitudinal axis of the delivery pipe, and each of said passages being diametrically opposite another of said apertures, a deflector permanently and rigidly supported across each of said education apertures and having its marginal edges extending beyond the edges of said aperture uniformly, each of said deflectors having a concave outer face and a convex inner face extending into the adjacent aperture and spaced uniformly from the edges thereof to form a discharge slit, having an area substantially equal to that of the adjacent education passage, and a sleeve surrounding each of said deflectors, coaxial with the adjacent education passage and spaced uniformly from the marginal edges of the adjacent deflector, to form a surrounding passage of greater area than the adjacent discharge slit, each of said sleeves extending over the adjacent discharge slit, and having an aperture at its outer end of greater area than the adjacent education passage.

7. In a chimney cap or ventilator, the combination with a vertically disposed delivery pipe closed at its upper end and provided with a plurality of horizontally disposed education passages communicating therewith, provided with outwardly flaring ends terminating in education apertures of greater area than the main portions of said passages, said passages extending in different directions radially with respect to the

longitudinal axis of the delivery pipe, a deflector permanently and rigidly supported across each of said eduction apertures, said deflectors having at least as great an area as said flaring apertures, and being spaced uniformly from the edges of said apertures to form a discharge slit of an area substantially equal to that of the adjacent eduction passage, and having convex portions projecting into said flaring apertures,

a sleeve surrounding the flared portions of each of said eduction passages, coaxial therewith and spaced uniformly from the edges of said deflector and eduction aperture, and a vertically disposed stationary partition in 15 the upper portion of said eduction passages, and substantially in alinement with the longitudinal axis of the delivery pipe.

In testimony whereof I affix my signature.

ARTHUR F. BRASSINGTON.
